ILLUMINATED MUSIC RACK

Webster E. Janssen, Westport, Conn.

Application March 15, 1940, Serial No. 324,050

3 Claims. (Cl. 240—4)

This invention relates to illuminated music racks and is herein described in some detail as embodied in a music rack or support which is adapted to be built into one of the most compact forms of modern standard-keyboard pianos and which may also serve to throw shielded light on the keys thus enabling the piano to be easily played in a darkened room with light on both the music and the keys.

One of the annoying problems which seriously disturbs musicians in playing a piano is the proper lighting of sheet music which for the convenience of the musicians stands on the usual music rack above the keyboard, and the rack often forming part of the front of the upper casing of the piano.

Often the most satisfactory lighting of the music is obtained by placing a lighted high-standard floor lamp near one shoulder of the musician. Attempts have been made to provide attachments to be affixed to the piano to provide suitable lights and racks, but they are awkward to attach to many pianos, must be attached carefully to avoid marring the piano, are exposed and so become gatherers of dust, and do not ordinarily fit at the most convenient height for the musician.

According to the present invention, the foregoing and other objections and disadvantages are overcome, and a piano-music lighted support is provided which may be built into many of the most compact pianos, does not project from the piano when not in use, holds the music at the most convenient height, and is well adapted to be used in a darkened room so as to give the musician a highly effective lighting of both music and keys and yet throw no light elsewhere to blind the eyes of an audience.

The invention is herein disclosed in some detail as embodied in a compact piano having a horizontally sliding fall board which slips backwardly away from the keys.

In the form shown the shelf above the fall board, or, at least, the central portion of the shelf is slideable forwardly and the front part of the shelf is adapted to be swung upwardly and backwardly so as to become a music rack.

In the form shown, the lifting of the rack uncovers a light concealed beneath the shelf so that the light may shine upwardly and rearwardly against sheet music resting on the shelf, thus effectively illuminating the music by light wholly concealed from the musician and audience.

The light is shown as shining through a trans-

parent sheet which forms part of the rest on which the music may be set.

If desired the light may also shine through a front slot to illuminate the keyboard.

5 When the music rack is out of use, it is shown as usually swung forwardly and downwardly to cover the light and then pushed rearwardly until the top of the rack becomes the front of the shelf.

10 If desired the light may be normally extinguished and only lighted when the rack is swung upwardly.

Other features and advantages will hereinafter appear.

15 In the accompanying drawings,

Figure 1 is a sectional side view of one embodiment of the invention taken on the line 1—1 of Figure 3.

20 Figure 2 sectional front view of the same taken on the line 2—2 of Figure 1.

Figure 3 is a top view of the parts seen in Figure 1 with the slideable section in closed position.

25 Figure 4 is a sectional side view on the line 4—4 of Figure 3.

Figure 5 is a sectional front view of a roller track for the rack roller on line 5—5 of Fig. 3.

Figure 6 is a sectional side view of the track of Figure 5 on the line 6—6 of that figure.

30 The invention is shown as embodied in a commercial form of piano in which keys 10, at the front ends of downwardly extending levers 11, lie behind a lip 12.

35 A horizontally fall board 13 may be drawn forward upon slides 18 to cover the keys and its pivoted front portion 15 may be dropped to close the space in front of the keys.

In the form shown the fall board 13 is caused to move parallel to itself by a rock shaft 16 extending across the piano above the key levers 11, and carrying at each end a rock arm 17, pivoted to a link 17', which in turn is suitably pivoted to the fall board 13.

40 The fall board 13 is arrested at the front end of its travel by stops 19 which limit the throw of the rock arms 17, and is arrested at the rear end of its travel by a stop 20.

The type of piano shown, usually includes an upper front wall 22 above the fall board with a shelf 23 between the fall board and the upper front wall 22. According to the embodiment of the invention shown the shelf 23 includes fixed end sections 24 and a central slideable section 25.

45 In the form shown, the central slideable section 25 takes the form of a music rack carried on end

5 pivots or rods 26 near its foot, said pivots sliding in rails or tracks 27 so that when it is swung forwardly and downwardly it may be pushed rearwardly beneath the bottom 28 of the wall 22 until it strikes a rear stop 29, and its front end rests on small felt buffers 30, near each margin of the section or rack 25.

To cause the rack 25 to slide easily and smoothly parallel to itself, in the form shown there is provided a rock shaft 31 journalled at the back of the wall 22 well above the tracks 27, and the rock shaft 31 carries at each end a rock arm 32 pivotally connected to a link 33, the links being shown as hinged to the foot 34 of the rock 25.

When the rack 25 stands nearly upright, in position to hold sheet music, the pivots 26 rest in detaining depressions 35 at the front ends of the tracks 27, thus holding the front face 36 of its base against the back of a removable cross or foot wall 31, with the result that the rack 25 naturally falls back a little into music-holding position and is held by the depressions 35 just clear of the top 58 of the front wall 22.

10 In its upright position the rack 25 is shown as lighted by an electric light 39, shown in the form of an elongated bulb lying horizontally along the back 40 of a lower front wall 41, shown as just above the front edge of the fall board 13 when the fall board is in its rearmost position.

The bulb 39 lights up any music resting on the rack 25 because the cross wall 31, shown as a flat board, contains a glass or other transparent strip 42 overlying the bulb 39 resting in rabbits 43 of the foot wall 31. To facilitate the resting of music on the cross wall 31, and to aid in the backward throwing of the light from the bulb 39, the cross wall 31 is shown as sloping rearwardly so that it makes about a right angle with the rack 25 as it lies inclined almost against the edge 38 of the wall 22.

15 The glass strip 42 is shown as also resting on a rear rabbit 44 of the ornamental front 45 of the cross wall 31.

The light of the bulb 39 is additionally thrown upwardly and rearwardly by a bent metal reflector 46, forming about a semi-circle around its bottom and front.

To keep the heat of the bulb 39 away from the key levers and finely finished fall board 13, the cross board 47 above the fall board 13 is shown with its top covered by an asbestos mat 48.

The bulb 39 is shown as utilized to light the front 49 of the keys 10. For this purpose a downwardly inclined narrow slot 50 is provided in the front wall 41, so set that the slot throws the light on the keys while concealing any direct light, and it is slightly tapered inwardly from its outer face 51, and as shown in Figure 2, is tapered to flare at its ends 52 to throw light towards the end keys 10 of the piano keyboard.

5 If desired the bulb 39 may be normally dark, and the switch 53 for controlling it may be an automatic switch which has a felt top 54 tending to rise and light the bulb but cutting off the light when depressed.

To enable incoming air from the slot 50 to escape and thus cool the bulb 39, vent holes or perforations 55 are shown in the wall 37, just behind the glass strip 42.

10 To enable the light from the bulb 39 to pass through the slot 50, there is provided an aligned slot 56 in the reflector.

The music rack 25 is shown with a projecting central handle 57 which also serves to add to the overweighting of its front and causes it to lift its pivots 26 out of the depressions 35 when resting on the felt buffers 30, with the result that it slides back easily.

15 In cases where the heat of the bulb 39 is considered serious, it may be replaced by an elongated tube of the so-called cold light of the fluorescent type.

20 Having thus described certain embodiments of the invention, what is claimed is:

25 1. A lighting device for a keyboard musical instrument including a front instrument wall having a slot therein parallel to the keyboard, a footboard extending rearwardly from the top thereof, a music rack cooperating with said footboard to support sheet music, a lamp behind the wall and below said footboard, a light transmitting strip in the foot board to permit the light from said lamp to illuminate said music, and a reflector for the lamp including a slot aligned with the wall slot through which light from said lamp illuminates said keyboard.

30 2. A lighting device for a keyboard musical instrument including a front instrument wall having a slot therein parallel to the keyboard, a footboard extending rearwardly from the top thereof, a music rack cooperating with said footboard to support sheet music, a cold type fluorescent lamp behind the wall and below said footboard, a light transmitting strip in the footboard to permit the light from said lamp to illuminate said music, and a reflector for the lamp including a slot aligned with the wall slot through which light from said lamp illuminates said keyboard.

35 45 3. A lighting device for a keyboard musical instrument, including a front instrument wall, a fall-board for the keys slidable in and out beneath the wall, a music support adapted to form part of a shelf, a lamp behind the wall and above the fall-board, a footboard against which the support rests to support music, a transparent strip in the footwall to cause the light to shine on music on the rack, and a reflector for the lamp including a slot through which light shines from the lamp through a slot in the wall on the keys.

60 WEBSTER E. JANSSEN.
